ATTORNEY

UNITED STATES PATENT OFFICE

JOHN A. RYMER, OF ALAMEDA, CALIFORNIA, ASSIGNOR, BY MESNE ASSIGNMENTS, TO
RY-LOCK COMPANY, LTD., OF RENO, NEVADA, A CORPORATION OF NEVADA

DOORLOCK

Application filed March 31, 1926. Serial No. 98,724.

My invention relates to door locks, and particularly to locks of the latch-bolt type having the bolt thereof arranged to be normally withdrawn by means operable from either side of the door.

An object of the invention is to provide a lock of the class described in which the normally acting latch operating mechanism may be rendered inoperative from a given side of the door, and in which means are provided for operating the latch independently of said first operating mechanism from other than said side of the door.

Another object of the invention is to provide a lock of the character described having a simple positioning means associated therewith of such structure that a lock may be positioned with the bolt thereof in desired relation between the sides of a door without necessitating any change in the lock or bolt structure.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a vertical sectional view of one embodiment of the lock of my invention installed in a door.

Figure 2 is a view taken on the line 2-2 in Figure 1.

Figure 3 is a view taken on the line 3-3 in Figure 1.

Figure 4 is a fragmentary view taken on the line 4-4 in Figure 1.

Figure 5 is a view showing various casing and positioning members associated with the lock shown in the preceding figures, such members being in separated and operatively aligned relation.

Figures 6 and 7 are fragmentary longitudinal sectional and end views respectively

of a knob spindle and mounting therefor forming part of the lock structure.

Figure 8 is a horizontal sectional view of another embodiment of the device.

Figure 9 is a view taken on the line 9-9 in Figure 5.

Figure 10 is a plan view of a portion of the structure shown in Figure 8.

Figure 11 is a horizontal sectional view of a modified form of the structure shown in Figure 8.

In the embodiment illustrated in Figures 1 to 9 inclusive, the lock 9 of my invention is shown positioned in a suitable cavity 10 provided in the edge 11 of a door 12, and is arranged to be operated from one side of the door by means of a knob 13 and from the other side of the door by means of a thumb latch 14. The bolt operating mechanism of the lock is mounted in a lock casing 16 which latter is arranged to be adjustably held positioned in the cavity 10 by means of a positioning device to be hereinafter more particularly described. As here shown, the casing 16 comprises a cylindrical shell portion 17 which is preferably closed at one end by a portion 18 formed integral therewith. The latch-bolt associated with the lock may be of any suitable form, a shank portion 19 thereof being here shown extending radially through and from the casing.

Normal operation of the latch bolt, it will now be noted, is arranged to be effected through the movement of a latch plate member 21 mounted for reciprocation diametrically across the casing in a line parallel to the line of movement of the bolt and with which the bolt shank 19 is operatively associated. As here shown, the member 21 comprises a plate portion 22 carried on guide rods 23 fixed to and extending across the casing 16 in parallel relation to the shank 19 and perforated to slidably receive the shank in transverse relation therethrough. To insure the maintenance of the member 21 in fixed angular relation to the shank, the plate 22 is here shown formed with portions 24 extending transversely therefrom at the latch side of the plate and having the extremities thereof turned inwardly and perforated to slidably

receive the rods 23. Fixed at the inner end of the shank 19 is a stop member 26 which, as here shown, is set in a slot extending diametrically through the shank end. The member 26 is positioned inwardly of the plate 22 so that a movement of the latter in the direction of the inner end of the shank will move the shank with it, it now being particularly noted that independent inward movement of the shank is thus permitted.

Actuation of the latch plate 21 to withdraw the bolt is arranged to be effected upon operation of the thumb latch 14 by means of suitable operative connections between the thumb latch and bolt. As here shown, the thumb latch is fulcrumed in a bearing 31 provided in an escutcheon plate 32 associated with the lock and is provided with an inwardly extending lever portion 33. Pivotally mounted on a pivot pin 34 extending from the outer surface of the casing end 18 is a bell crank 35, the latter having one arm 36 slotted to engage a pin 37 which extends from an adjacent portion 40 of the latch plate through a slot 38 provided in the casing end 18, and having the other arm 39 arranged to be operatively engaged by the lever portion 33 of the thumb latch. In this manner, it will now be readily understood that depression of the thumb latch will cause the withdrawal of the bolt.

It will now be noted that in order that the lock may be used with equal readiness in right-hand or left-hand doors, a second pivot 34' for the bellcrank 35 is provided on the outer surface of the casing end 18 on the opposite side of the slot 38. In this manner, it will now be clear, turning the casing end to end in the door cavity 10 from the position here shown and mounting the bellcrank on pivot 34' will allow a normal operation of the bolt by the thumb latch from the other side of the door, so that full reversibility of the lock is thus provided in a simple manner.

Operative movement of the latch plate is also arranged to be effected upon rotation of the knob 13. In the present embodiment, the knob 13 is mounted upon a spindle 41 having the outer portion thereof arranged to extend into the spindle cavity of the knob and to be held fixed therein by any suitable means, it being noted that knobs of usual structure may thus be used on the spindle. As here shown, the inner end portion 42 of the spindle is cylindrical and is mounted for rotative and reciprocative movement in a sleeve 43 extending transversely outwardly of and forming part of a plate 44 which is arranged to be secured to the casing shell 17 across its open end by means of the engagement of lugs 46 provided in the plate 44 and arranged to engage in L-shaped slots 47 formed in the shell edge, it being noted that the plate may thus be secured to the shell without use of

extraneous means such as screws or the like. The spindle, it will be noted, is preferably, and as here shown, positioned axially of the shell 17 so that a desirable symmetry of structure may be produced.

Means are provided on the inner end of the spindle portion 42 for normally engaging the adjacent edge 48 of the plate 22 in such manner that rotation of the spindle will cause the movement thereof to retract the bolt. As here shown, such means comprises a substantially semi-circular extension 49 formed integral with the spindle across its end and having its center of curvature in the axis of the spindle so that its outer face will bear against the inner face of the plate 44 to prevent removal of the spindle through the sleeve 43. Mounted on the inner face of the extension 49 and protruding inwardly therefrom into the plane of movement of the plate edge 48 is a pair of latch plate engaging members 51. As here shown, the members 51 comprise rollers of equal size, it being noted that they are so positioned with respect to the spindle that one common tangent thereto parallel to their line of centers is diametral of the spindle and that the plate edge 48 normally engages them along such tangent. It will now be noted that the members 51 serve to provide a stop to limit the forward movement of the latch plate, and since, as hereinbefore pointed out, the stop 26 on the bolt shank serves to limit the forward movement of the bolt shank through the plate 22, limitation of the outward movement of the plate and bolt is thus provided. To hold the latch bolt in its normally outward position, a spring 52 is preferably interposed between the inner end of the bolt shank 19 and the opposed portion of the wall of the shell 17, while the plate 22 is arranged to be held in engagement with the members 51 by means of one or more springs interposed between it and the shell wall, a pair of helical springs 53 being here shown conveniently mounted on the guide rods 23 for the purpose. In this manner, rocking of the knob and spindle in either direction will cause a rocking of one of the members 51 against the latch plate edge 48 to thereby cause a backward movement of the latch plate, it being noted that by reason of the bolt spring 52 and latch plate springs 53, the spindle will be normally so positioned that both rollers 51 will engage the adjacent side of the latch plate edge 48, so that a fixed relation of the spindle and extension will normally be maintained.

It will now be obvious that by preventing the movement of the latch plate, the withdrawal of the bolt by operation of either the thumb latch or knob would be prevented, and since it is one of the objects of the invention to cause the holding of the latch plate against movement by means operable from the inside or knob side of the lock, the spindle end por-

tion 49 is conveniently utilized in accomplishing such purpose. Accordingly, a transverse slot 56 is provided in the end of the spindle portion 49, said slot lying opposite the adjacent edge of the latch plate when the latter is its normal position against the rollers. It will now be noted that when the spindle is rotated under normal conditions, the plate edge 48 will be permitted to move over the portion of the spindle end lying rearwardly of the rollers but that inward displacement of the spindle to cause engagement of the edge 48 in the slot 56 will prevent an operative displacement of the latch plate by either the thumb latch or knob. It will now be clear that there are two operative positions of the spindle, and means are accordingly provided for positively retaining the spindle in one or the other of said positions. As here shown, such spindle positioning means comprises the provision of a pair of detent receiving grooves 57 inside the sleeve 43 and spaced apart longitudinally thereof a distance equal to the desired distance of movement of the spindle and in which suitable detent means are arranged to seat. As here shown, the detent means comprises the provision of a perforation 58 within the spindle portion lying within the sleeve, such perforation extending diametrically through the spindle and having a spring 59 mounted within it which is arranged to simultaneously urge outwardly a pair of ball detents 61 seated at its opposite ends. The grooves 57, it will now be noted, are preferably annular so that both detents are simultaneously operative in each of the limiting positions of the spindle. In this manner the spindle will be normally held positively positioned in either extreme position, yet its release is readily accomplished upon exertion of a slight pushing or pulling force as the case may be.

It will now be noted that a means has been provided to either permit or prevent the normal actuation of the latch plate by the knob and thumb latch simply by appropriately positioning the spindle in an outer or inner position so that the lock of my invention may thus be made to function interchangeably as a latch or a bolt lock in a very simple manner.

Since locks of the type shown are normally used for outside doors, key operated means are provided for withdrawing the bolt independently of any movement of the latch plate 21, so that with the latter in locked position, the door may be opened from the outside by the use of a key. As here shown, such means comprises a housing 63 mounted in the escutcheon plate 32 and having the major portion extending rearwardly of the plate and into an appropriate cavity 64 provided in the door and communicating with the lock cavity 10. Mounted in the housing 63 for rotation about its axis is a key receiving barrel 66, said barrel being arranged to be rendered

rotatably only upon the insertion of a proper key therein, it being noted that the exact structure and operation of the barrel releasing means is immaterial to the present application.

The before-mentioned independent operation of the latch bolt 16, it will now be noted, is arranged to be effected by means of the direct actuation of the bolt shank 19 independently of the latch plate 22, operative connection between the bolt shank 19 and the key operated barrel 66 being effected in any suitable manner. As here shown, such connection is provided by means of a bell crank lever 67 mounted on the plate 44 and having one arm 68 thereof operatively associated with the shank stop member 26 while the other arm 69 thereof is operatively connected to the key barrel 66 by means of a link 71. The barrel 66, it will be noted, is provided with a longitudinally extending perforation 72 near its periphery in which a pivot pin 73 having the end thereof fixed to the link 71 is slidably and adjustably mounted. Mounting for the bell crank 67 is provided by forming it to fit over the sleeve 43 which thus serves to provide a pivotal anchorage for it. Extending outwardly from the shank stop member 26 through the plate 44, is an extension 74, the plate 44 being provided with a slot 76 to permit the free reciprocation of the extension 74. It will now be noted that the rotation of the barrel through a substantial angle from the position shown in Figure 2 will cause the movement of the lever arm 68 through such a distance that the extension 74 will be correspondingly moved to draw back the latch bolt, even though the latch plate 22 be held fixed in the manner hereinbefore described. It will also be noted that the crank lever arm 68 is arranged to slidably and obliquely engage the extension 74 so that the resilient pressure of the bolt spring 52 will resiliently resist the rotative displacement of the bell crank with such force that upon removal of the key therefrom, the barrel will be rotated to restore the bell crank to its inoperative position, so that the lock will thus function as a key-latch.

It will now be noted that since it is usually desirable that the latchbolt be positionable in doors of various thickness in some predetermined relation between the sides thereof, a mounting means for the lock has been provided which will permit such positioning of the latchbolt without effecting the structure either of the lock or latch. Accordingly, and as shown in the present embodiment of the invention, the lock casing portion 16 is arranged to slidably and justably engage a pair of lugs 77 secured to and extending from the rear face of the escutcheon plate 32 through perforations 78 provided in the end 18 of the casing 16 whereby they may lie against the inner face of the casing shell 130

portion 17. Cooperating means on the casing and lugs are provided for releasably holding the casing in desired position on the lugs. As here shown, such means comprises the provision of slots 79 in the shell 17 through which the shank 81 of flat headed screws 82 mounted in threaded engagement with the lugs extend, so that the shell wall may be gripped between the screw heads and the lugs when in adjusted relation. Cooperating means for holding the casing positioned are provided at the knob side of the lock mechanism. As here shown, such means comprises a mounting plate 84 having an edge portion 86 arranged to engage the door around the edges of the cavity 10 and a central portion 87 perforated to engage around the sleeve 43 of the plate 44. The sleeve 43 is externally threaded and a nut 88 is provided for threaded engagement therewith so that with the casing fixed on the lugs and the plate 84 in position, the screwing down of the nut on the sleeve outside of and against the plate 84 will clamp the door between such plate and the escutcheon plate and thus insure a firm positioning of the lock in the door. By forming the edge and central portions of the plate 84 in offset relation, as here shown, the plate 84 may be applied either with the portion 87 inwardly of the door surface as particularly shown in Figure 1, or outwardly thereof, the plate being applied in the latter position for lock installations in very thin doors to provide the necessary clearance between the mounting plate 84 and the casing plate 44. A face plate 89 is also provided which is arranged to be fixedly positioned over the plate 84 and is provided with a sleeve portion surrounding the inner portion of the knob 13 in such manner that its inner and outer positioning may be effected without exposing the spindle 41 to view.

The embodiment shown in Figures 8 to 10 inclusive, comprises a lock 101 particularly arranged for interior installations, as for bedrooms and bathrooms, where a key lock is not needed. The lock of this embodiment is arranged to be normally operated from both sides of a door 102 by means of knobs 103 and 104. The latch bolt shank 106 and latch plate 107 associated with the lock are mounted in a casing 108 and are of similar structure to the corresponding members of the previously described embodiment. The casing, it will be noted, comprises a cylindrical shell 109 having one end plate 111 formed integral therewith and the other end plate 112 removably fixed thereto, both of said plates being provided with outwardly extending sleeve portions 113 and 114 respectively in which knob spindles 116 and 117 fixed to the knobs 103 and 104 are engaged. The spindle 117, it will be noted, is of similar structure to the knob spindle 41 of the previously described embodiment, and

is arranged to be manipulated similarly thereto with respect to the latch plate 107, while the spindle 116, on the other hand, lacks a latch plate engaging groove and is thus not arranged for longitudinal displacement. In this manner, the inward positioning of the knob 104 will render both knobs inoperative to move the latch plate, it being obvious that the knob 104 would be placed on the side of the door from which it is desired to perform the locking operation. 70

It will now be particularly noted that the bolt shank 106 forms a portion of a novel bolt structure. As here shown, the latch bolt 117 comprises the shank 106, a connecting 80 stem 118 and an outer detent portion 119, the latter being preferably of rectangular section and presenting the usual bevelled face 121 on its exposed portion. One end of the stem portion 118, it will be noted, is arranged 85 for threaded engagement in the portion 119, a lock nut 122 being utilized to secure these portions in adjusted relation. The other end of the stem 118 is arranged to engage and be held within a socket 123 provided in the 90 outer end of the shank 106. As here shown, the socket is provided at its end with an L-shaped slot opening in which a pin 124 fixed to the stem is arranged to engage to hold the stem against longitudinal removal 95 from the shank socket. The bolt portion 119 is arranged for reciprocation through a perforated face plate 126 whereby it may be guided and its rotation prevented when it is operatively disposed in the door edge. As 100 here shown, the plate 126 is provided with an inwardly extending guide plate portion 127 at the same side as the bevelled bolt face 121, while the under side 128 of the plate is preferably corrugated or fluted as here shown to 105 prevent lateral and rotative displacement of the plate when fixed to the door by means of the screws 129. The foregoing described bolt structure is particularly valuable in installing locks, since with bolts of the usual 110 types which are fixed in length, their first installation requires great care as to the exact positioning of the lock mechanism associated therewith, and no adjustment is possible in the event of swelling, shrinkage, or 115 warping of the door. Adjustment of the present device, on the other hand, may be readily effected by removing the plate 126 to allow turning of the outer bolt portion to release the stem from the shank 106 and thus 120 permit the removal of the stem and bolt head assembly for relative adjustment. It will now be particularly noted that the bolt structure (119—118—106) now described is 125 preferably utilized in the first described embodiment.

Since in rooms such as bathrooms and sick rooms, it is frequently desirable that it be possible to unlock the door from the outer side, and since the lock now described lacks 130

a key operated mechanism for this purpose, means are provided for effecting such unlocking. As here shown, an arm 131 is pivotally secured to the casing end plate 111 adjacent its edge, said arm being provided with a polygonal aperture 132 in its axial line which is arranged to receive a suitable member for rocking the arm, such member being here shown in the form of a thumb-turn 133 mounted in and extending through the positioning plate 134 and face plate 135 of the lock. A shank stop extension 136, it will now be noted, is provided for engagement by the arm 131, so that rocking of the thumb turn 133 may cause withdrawal of the bolt even though the latch plate be locked in position. In this manner, opening of the door by turning the knob may be prevented, yet deliberate turning of the thumb-turn 133 will permit opening of the door, it being noted that the opening means thus provided corresponds in its function to the key lock mechanism of the previously described embodiment.

The embodiment of Figure 11 is a modification of the preceding embodiment and differs therefrom chiefly in the lock of any means for opening the locked door from the outside. It will be noted that in this, as in the preceding described embodiments, that the bolt is freely retractile when pressure is exerted directly on it. But since with the spindle 117 in locking relation to the latch plate 147, a door might be slammed shut with no one on its inside to release the lock, means are provided for preventing such contingency. As here shown, the spindle end portion 141 lying between the rollers 142 is bevelled toward the bolt side thereof, and the incline thus provided is arranged to be engaged by a pin 143 adjustably fixed on the bolt shank in opposed relation thereto in such manner that if the spindle be in its inner position and the bolt is pressed inwardly, the spindle will be forced outwardly to its unlocked position, so that in this manner, accidental locking of the door is prevented.

It will now be particularly noted that the herein-described lock structures of my invention all include the performance of the locking function by means of a longitudinal positioning of a spindle knob, and that the majority of parts used in the various embodiments are common to all, so that a minimum number of parts need be manufactured and a change from one type to the other is simply effected.

I claim:

1. In a lock of the class described, a normally extended latch bolt, a movable latch plate operatively engaging said latch bolt, manually operable means arranged to effect the movement of said latch plate to withdraw said bolt, means arranged to be set by

and upon an appropriate manipulation of said first means to prevent said movement of said latch plate, and means permitting the inward movement of said bolt independently of said latch plate.

2. In a lock of the class described, a normally extended latch bolt, a latch plate operatively engaging said latch bolt, means normally operable to retract said latch plate and actuatable to prevent the operative movement of said latch plate, and means engaging said latch bolt and operative to effect the retraction of said bolt independently of said latch plate.

3. In a lock of the class described, a normally extended latch bolt, a latch plate operatively engaging said latch bolt, means operative from one side of said lock operatively engaging said latch plate, means operative from the other side of said lock to effect a retraction of said latch bolt, means operable upon an appropriate manipulation of the former of said operating means for rendering both of said operating means inoperative, and means arranged to permit the retraction of said bolt while said operating means are inoperative.

4. In a lock of the class described, a normally extended latch bolt, a latch plate operatively engaging said latch bolt, means operative from one side of said lock operatively engaging said latch plate, means operative from the other side of said lock to effect a retraction of said latch bolt, means operable from one of said sides of said lock to render both of said operating means inoperative, and means operable from the other side of said lock for retracting said latch bolt when said operating means are inoperative.

5. In a lock of the class described, a normally extended latch bolt, means operable from either side of said lock to cause the retraction of said bolt, means associated with said first means operable at one side of said lock for rendering said first means inoperative, and means operable from the other side of said lock for retracting said bolt while said first retraction means is inoperative.

6. In a lock of the class described, a normally extended latch bolt, a latch plate operatively engaging said latch bolt, means including a knob and spindle positioned at one side of the lock and arranged to actuate said plate upon the rotation of such means, means positioned at the other side of the lock arranged to be manually manipulated to actuate said plate independently of said first means, means permitting an inner and outer positioning of said spindle, and means operative upon said inner positioning of said spindle to fixedly secure said latch plate and thereby render said plate actuating means inoperative.

7. A lock of the class described and in accordance with claim 6 characterized by

having independent means operable to retract the plate and bolt.

8. A lock of the class described and in accordance with claim 6, characterized by having means arranged at the opposite side of the lock from said spindle and adapted to be operated independently of said plate operating means to cause the retraction of the plate and bolt.

10. A lock of the class described and in accordance with claim 6, characterized by having a bolt retracting means operatively associated with the bolt and operable independently of the latch plate and from the opposite side of the lock from the spindle.

15. 10. In a door lock of the class described, a normally extended latch bolt, a bolt operating mechanism operatively and releasably associated with said bolt, a supporting casing for said mechanism adapted for positioning in said door, a plate member arranged to engage a side of said door, means on said plate member cooperating with said casing whereby said casing may be adjustably fixed to said 20 plate in transverse spaced relation therefrom, a second plate member arranged to engage the opposite side of said door in opposed relation to said first plate and said casing, and means cooperating with said casing and second plate whereby said latter plate may be urged toward said first plate to clamp said door between said plates and tensionally position said casing between them.

11. In a door lock of the class described, a bolt operating mechanism including a latch plate; a normally extended retractible latch bolt operable by said mechanism and comprising a latch plate engaging portion, a head portion, and an intermediate connecting portion, said portions being longitudinally aligned; means adapted to secure said intermediate portion of said bolt to said head portion in adapted fixed relation thereto; means operative to secure said intermediate portion 45 of said inner portion and releasable upon relative rotation of said portions about their common axis, and means positioned on the door and slidably engaging said outer bolt portion whereby the rotation of said outer 50 and intermediate bolt portions to effect their disengagement from said latch plate engaging portion is prevented.

12. In a lock of the class described, a normally extended latch bolt, a bolt operating 55 mechanism operatively and releasably associated with said bolt, a supporting casing for said mechanism adapted for positioning in said door, plate members disposable at opposite sides of the door, and means adjustably 60 securing said casing to and between said plates whereby the plates may be urged together to clamp said door between the plates and tensionally position said casing between them.

13. In a lock of the class described, a normally extended latch bolt, a movable latch

plate operatively engaging said latch bolt, a spindle normally rotatable and arranged to actuate said plate upon a rotation thereof, means permitting an axial displacement of said spindle from the normal position thereof to a second position, and means operative upon the positioning of said spindle in said second position to fixedly secure said latch plate and thereby render said spindle inoperative.

14. A lock of the class described and in accordance with claim 13, having detent means yieldingly securing the spindle in each of its positions.

15. In a lock of the class described, a normally extended latch bolt, a reciprocable latch plate actuatable to withdraw said bolt, a spindle longitudinally adjustable between a pair of limiting positions, and cooperatively engageable means on said spindle and latch plate whereby when said spindle is in one of said positions a rotation thereof is permitted for withdrawing said bolt and when said spindle is in the other of said positions said spindle and latch plate are interlocked against 90 rotation and reciprocation respectively.

In testimony whereof, I have hereunto set my hand at Oakland, California, this 23rd day of February, 1926.

JOHN A. RYMER.
